CHARLES E. STOCKFORD, OF BROOKLYN, NEW YORK, ASSIGNOR TO STANDARD OIL COMPANY OF NEW YORK, OF NEW YORK, N. Y., A CORPORATION OF NEW YORK.

DISTILLING PETROLEUM UNDER HIGH PRESSURE.

1,425,712.

Specification of Letters Patent. Patented Aug. 15, 1922.

Application filed May 8, 1915. Serial No. 26,801.

To all whom it may concern

Be it known that I, CHARLES E. STOCKFORD, a citizen of the United States, residing at New York city, Brooklyn Borough, 5 Kings County, in the State of New York, have invented certain new and useful Improvements in Distilling Petroleum Under High Pressures, of which the following is a specification.

10 This invention relates in part to the construction and use of a special still setting, and in part to a special method of firing the still, all in connection, at least primarily, with the distillation of petroleum at 15 composing temperatures and under high pressures, say seventy to seventy-five pounds per square inch above atmospheric pressure with the oil in distillation at temperatures above 700° F. Each of the improvements composing the invention is intended to 20 be secured for all the uses to which it can be applied with or without modification; but the invention is not concerned with settings for steam boilers, methods of firing 25 steam boilers and the like; whose functions as a whole are unlike those performed by the said special still setting and the said special method of firing the still. Omissions, substitutions and additions can be 30 made indefinitely, so long as the substance is retained of any one or more of the claims at the close of this specification.

For firing the still it is considered advantageous to use an open topped fire chamber and an open topped communicating flue (with intervening bridge wall and with gas burners in the flue); above which fire chamber, bridge wall, flue and gas burners the still is mounted. With these heating 40 means difficulty was at first experienced from overheating the still bottom above the bridge wall, which resulted in the bulging out of said still bottom at this point in the form of pockets and which consequently involved repeated repairs performed by suitably heating the bulged out metal with a 45 flame of aeriform fuel and oxygen and then pressing it back to its original position. The present inventor has discovered that 50 this local overheating can be largely at least avoided without diminishing the heating effect needed to maintain the still contents at the desired high temperatures by establishing such a distance between the bottom 55 of the still and the top of the bridge wall

that the flames from said fire chamber are deflected into a direction more nearly horizontal than vertical by the time they reach the still bottom. Said distance should be upwards of a third of the diameter of the 60 still in order that sufficient deflection may take place in the large volume of fire gases flowing from the fire chamber over the bridge wall thereof.

In the accompanying drawings:

Fig. 1 is a view in section and elevation of apparatus in accordance with the invention;

Fig. 2 is a view in plan of portions of the appliances for conducting vapors from the 70 still;

Fig. 3 is a detail view of a vapor expansion valve, which may be used or not, as may be preferred;

Figs. 4, 5 and 6 are views in section illustrating the manufacture of the still proper;

Figs. 7 and 8 are detail views of a portion of the firing means; and

Fig. 9 is a detail view of sediment collectors (false bottoms) within the still.

The still *a*, which may be taken to be about ten feet in diameter by about forty feet in length, may be composed of four body sheets *b* of rolled steel, each about ten feet wide by about thirty feet long, and two 85 heads *c*, each about ten feet in diameter. The heads *c* are swaged or otherwise brought into the flanged form shown; and one at least of them is provided with a man-hole. Each body sheet is bent into annular 90 form with the margins lapped (Fig. 6) and is retained in this position by clamps *d*, which are spaced from the still sheet by washers *e*; and whose ends are secured by bolts *f*. The bolt holes are filled when the 95 bolts shall have been removed.

The lapped margins are heated locally to welding temperature by means of a flame of aeriform fuel and oxygen (air). Apparatus for producing such flames is known 100 and is not represented. The clamps *d* are removed whenever they are in the way. When a convenient length has been heated, the overlapped margins therein are compressed and unified by hammering, an anvil 105 (not shown) being placed on the inside.

One of the so formed annular still sections is united in a similar way to one of the still heads. For example, the margin at one end of the section can be swaged outwardly 110

and slipped over the flange on the still head; and the parts can be held together by clamp rods *g* during the heating and hammering. As shown, these rods are hooked at one end over the edge of the still section and connected at the other end with a yoke *h* by means of nuts *i* engaging screw threads on the clamp rods *g*. The clamps are shifted as required.

10 Still section is united to still section in like manner until a still body of the desired length has been obtained; and the second still head is then applied.

15 For retaining the second still head in place during the heating and hammering use may be made of clamp rods *j* connected at each end with yokes *h* by means of nuts *i* engaging screw threads on the clamp rods.

20 Until the second head is in place the anvil can be inserted and held through the open end of the last applied still section; and when the second head is in place it can be inserted and held through the manhole.

25 The manhole fittings *k*, the vapor discharge fitting *l*, the supporting brackets *m*, and other fittings can be secured in any suitable way. As they are not exposed directly to the fire gases, nor subject to expansion and contraction at a different rate 30 from the portion of the still to which they are attached, it is less important to have them practically integral with the still sheets than it is to have these practically integral with each other. In Fig. 4, however, one of the manhole fittings *k* is represented as being secured to the still head in the manner in which the still sheets are 35 united to each other; and this mode can be used also for other fittings. Referring to

40 Fig. 4, the margins of the manhole in the still head are spread outward; the fitting is slipped in; the parts are held together by clamp rods *n* and yokes or cross pieces *o p*, each clamp rod being headed at one end and 45 provided with a nut *i* engaging screw threads at the other. The lapped margins are heated to welding temperature, compressed and unified, the clamps being shifted as required.

50 In securing the brackets *m* to the still it is well to use rivets and to weld the inside head of each rivet to the wall of the still by the aid of the blast of aeriform fuel and oxygen (air) with such hammering as may 55 be necessary or expedient. Such welding may be performed in other locations where rivets are employed or otherwise. For example, the collars *q* can be so welded. The holes for bolts *f* of Fig. 6 can, for example, be filled by rivets; whose heads are then welded to the still sheet.

60 The thickness of the still sheets should correspond with the internal pressure which has to be supported. Sheets of boiler steel nine-sixteenths of an inch in thickness

would be appropriate for an internal pressure of seventy to seventy five pounds per square inch above atmospheric pressure.

What are considered the best heating means comprise an open topped coal burning fire chamber *r* and an open topped flue *s*, at the bottom of which (in grooves, Fig. 8) are located gas burners *t* in the form of perforated pipes. A grate *u* constitutes the bottom of the fire chamber; and below 70 it is the ash pit *w*. This last would ordinarily be closed to receive a forced blast from pipe *x*; because the cheapest form of coal does best with a forced blast; but it is not essential to the invention that fuel 80 requiring a forced blast should be used. The fire gases flow from the fire chamber *r* over the bridge wall *y* to the flue *s* and thence by a continuation flue *z* to the chimney. 2. A damper *3* is shown in flue *z* for checking 85 the draft as required, or for closing the flue *z* when necessary. Below each gas burner *t* is an air duct *4* roofed with a perforated plate *5*. At the outer end of each air duct is a damper, as indicated at 6 in Fig. 7. 90 Each burner *t* receives gas and air from a gas main and an air main (not shown) through valved branch pipes *7* and *8*, respectively.

The still *a* is mounted above the fire chamber *r* and flue *s* in such manner that the bottom thereof is exposed directly to the fire. The distance between the bottom of still *a* and the top of the bridge wall *y* should be upwards of a third of the diameter of the still *a*. For a still ten feet in diameter a distance of four feet six inches has been found advantageous and is considered as good as any. 95

The still *a* is upheld in any known or suitable way by means of the brackets *m*; and it is bricked in below said brackets in any known or suitable way; but it is considered desirable to expose to the fire only about a third (more or less) of the circumference 100 of the still; in order that the so exposed portion will remain covered with liquid when distillation has been carried as far as it would ordinarily be desirable to carry it under the high pressures mentioned. 115

From the fitting *l* a vapor pipe *9* leads to a water cooled condenser *10*; from which the pipe *11* leads to the tank *12*, having a valved liquid draw-off *13* and a valved gas escape *14*. The valves in these pipes *13* 120 and *14* enables the contents of the still *a*, condenser *10* and tank *12* to be held under pressure of the non-condensable gases evolved in the still *a*. Said valves can be opened to let off the accumulations of the 125 gases and of distillate respectively. The pressure can be shown by a gauge 150. If, instead of condensing the vapors in condenser *10* under the high pressures under which they are evolved in the still *a*, it 130

should be desired to effect condensation under atmospheric pressure, a suitable relief or expansion valve can be placed in the vapor pipe 9. In Fig. 3 a needle valve 15 is shown in a reduced descending portion of the vapor pipe 9 for this purpose.

The vapor pipe 9 is shown as rising from the still *a* in order that condensate found therein may run back into the still *a*. The exterior surface of this pipe is exposed to the atmosphere for cooling. The still *a* is shown as provided with a heat retaining jacket 16 over the top as well as over the ends; but, while considered advantageous, it is not considered essential that the still should be so jacketed.

The vapor pipe 9 would best be provided with a stop valve 17; which is normally full open in running; but which can be closed when for any reason it is desired to prevent the passage of the vapors onward in pipe 9. At such time branch pipe 18 would be opened to conduct the vapors away; say to a water cooled condenser (not shown).

While only one vapor pipe 9 and condenser 10 appears in Fig. 1, one or more may be used. In fact, it is considered advantageous for fitting *l* to be in the form of a T and to 30 be connected with two vapor pipes 9; as indicated in Fig. 2.

Within the still *a* is shown a sediment collector in the form of curved plates 19 separately hinged to the still wall on each side of the still and suitably spaced therefrom to allow the flow (indicated by arrows in Fig. 1) of oil and vapors between said plates and the still walls. Adjacent plates overlap at all their contiguous margins; so that the division between the underlying and the overlying spaces is continuous; and the liquid must enter and leave the underlying space at the margins only of the sediment collector. Plates which are hinged on opposite sides of the still interlock, as shown in Fig. 9. This prevents the plates from descending lower, but does not interfere with lifting them up on their hinges when desired; as, for example, 45 in cleaning the still in order to give access to the underlying still bottom. One or more sediment collectors (false bottoms) may be used. Two are shown in Figs. 1 and 9.

50 At each of the points 21 a manually operated valve is indicated. The still *a* is shown as provided with a steam inlet pipe 22 and a pumping out line 23. It would best be filled through one of the top manholes *k* from a conveniently located filling line (not shown). At 24 is a peep hole. At 25 is a tubule for connecting a safety valve, a pressure gauge or the like with the still.

65 The still *a* is filled to the desired height,

say 66% full. Until distillation commences the entire heating may well be performed by the fire of coal in fireplace *r*. During this time of bringing in the still it is not important that the flames should 70 be deflected into a position more nearly horizontal than vertical. Hence it is considered well to introduce a much larger volume of air under the grate of fire chamber *r* at this time than later. After a proper temperature has been attained, distillation 75 commences and is performed under the desired high pressure, say seventy to seventy five pounds per square inch above atmospheric pressure; supplementary heating is 80 performed by the combustion of gas (mixture of gas and air) from burners *t*; and the volume of air fed to the fire in chamber *r* and the outflow of products of combustion (controlled by damper 3) are so 85 adjusted that the flames from fire chamber *r*, passing out over the bridge wall *y*, are deflected into a position more nearly horizontal than vertical before they reach that portion of the still bottom which overlies 90 said bridge wall and consequently do not heat the still bottom so intensely at this place as they otherwise would. The volume of air fed to the fire in chamber *r* must be sufficient to maintain the still contents 95 at a temperature suitably above 700° F. to effect distillation under the desired pressure. With a still *a* of the above mentioned dimensions good results have been obtained with air supplied below grate *u* of chamber 100 *r* at the average rate of about three hundred and fifty cubic feet per minute (measurement under atmospheric temperature and pressure). This would be roughly in the ratio of about a cubic foot of air per 105 minute for each seventy-five gallons of still capacity, in other words about ten per cent of said still capacity; and such ratio can be taken as standard, but can be increased or diminished as much as may be 110 desired consistently with the two conditions of (1) supplying sufficient heat to the still while (2) causing the flames from chamber *r* to assume a direction more nearly horizontal than vertical above the bridge 115 wall *y* so as to avoid overheating the still bottom at this point. Inspection through peep hole 24 will enable the direction of said flames to be sufficiently perceived.

120 In a run under high pressure on distillate gas oil or fuel oil specific gravity 0.8620 derived from crude petroleum from Kansas wells and consisting mainly of hydrocarbons with boiling points above 572° F. the temperatures in the oil in distillation and 125 also in the vapors in fitting *l* were between 700° F. and 800° F. during about all of the run. Those in the vapors at the highest point of vapor pipe 9 were for the most part between 300° F. and 400° F. It re- 130

quired about fourteen hours to bring in the still and about thirty-four hours to complete the run distillate equal to between fifty and sixty per cent of the still charge 5 by volume being collected. These figures can be varied.

Hydrocarbons composing the gas oil or fuel oil are decomposed at the high temperatures; and lower boiling hydrocarbons 10 are formed; which pass over to the condenser 10 and are condensed therein as distillate.

At the close of the run the fires are drawn; and the distillate is collected for a 15 time. Then the stop valve 17 is closed; and the pumping out line 23 is opened; and when the pressure in the still has sufficiently fallen steam is let in from pipe 22. Later steam is shut off; manholes are opened; and 20 the powder which collects on the collecting plates 19 and on the still bottoms is swept up with wire brooms and shoveled out.

A petroleum still to be of practical size must have a capacity of not less than about 25 one thousand cubic feet; so as to receive a charge of not less than about five thousand gallons of petroleum, when say sixty-six per cent full, as herein above set forth. A still of ten feet in diameter and forty feet 30 in length, as herein above set forth, would, of course, have a capacity of about 3,000 cubic feet, and would receive a charge of about 15,000 gallons when 66% full.

I claim as my invention or discovery:

35 1. A high pressure petroleum still of horizontal cylindrical form provided with heating means in the form of an open topped fire chamber and an open topped heating flue communicating with said fire 40 chamber by an open topped passage over the bridge wall of the latter, so that the still bottom above said bridge wall and elsewhere over substantially its entire area between the side walls of the furnace is directly exposed to the fire gases flowing from said chamber over said bridge wall through said flue, said still being so disposed as to leave 45 between the bottom thereof and the top of the bridge wall a distance of upwards of a third of the diameter of the still, substantially as described.

2. A high pressure petroleum still of horizontal cylindrical form provided (1) with manhole and vapor discharge fittings, (2) 55 with means for holding the still contents under superatmospheric pressure, and (3) with heating means for raising the still contents to above 700° F., the said heating means being in the form of an open topped 60 fire chamber and an open topped heating flue communicating with said fire chamber by an open topped passage over the bridge wall of the latter, so that the still bottom above said bridge wall and elsewhere over 65 substantially its entire area between the

side walls of the furnace is directly exposed to the fire gases flowing from said chamber over said bridge wall through said flue, which said still is so disposed as to leave between the bottom thereof and the top of 70 the bridge wall a distance of upwards of a third of the diameter of the still, substantially as described.

3. The method of firing a high pressure petroleum still which has a capacity of not 75 less than about one thousand cubic feet and which has previously been charged with petroleum of appropriate character in suitable volume by bringing flames and fire gases directly into contact with the bottom 80 of the said still, suitably elevated above a bridge wall and having its said bottom directly exposed to said flames and fire gases above said bridge wall and elsewhere over substantially its entire area between the 85 side walls of the furnace, producing said fire gases in sufficient volume and at sufficient temperature to raise the contents of the still to decomposing temperatures above 700° F., and so adjusting the inflow of air 90 and the withdrawal of combustion products relatively to the area in cross section of the open topped passage above said bridge wall that the direction of the flames on reaching the still bottom above said bridge wall shall 95 be more nearly horizontal than vertical, substantially as described.

4. The method of firing a high pressure petroleum still at decomposing temperatures above 700° F. by means of an open topped 100 fire chamber and an open topped flue, both of them underlying said still, and communicating with each other by an open topped passage above a bridge wall under the still bottom at a distance therefrom of upwards 105 of a third of the diameter of the still, which said method consists in bringing flames and fire gases directly into contact with the still bottom, above said bridge wall and elsewhere over substantially its entire area between the side walls of the furnace, producing 110 said fire gases in sufficient volume and at sufficient temperature to raise the contents of still to decomposing temperatures above 700° F., feeding air at the rate of 115 about ten per cent per minute of the capacity of said still to the fire in said chamber as a standard, and regulating the withdrawal of the combustion products from said flue at such rate that the flames from said fire 120 chamber on reaching the still bottom above said bridge wall shall have become more nearly horizontal than vertical, as may be perceived by inspection through an appropriately located peep hole, substantially as 125 described.

5. A high pressure petroleum still of horizontal cylindrical form provided with heating means which are so proportioned relatively to the capacity of said still as to main- 130

tain the latter with its charge of petroleum at decomposition temperatures above 700° F. and which comprise an open topped fire chamber and an open topped heating flue 5 communicating with said fire chamber by an open topped passage over the bridge wall of the latter, so that the still bottom above said bridge wall and elsewhere over substantially its entire area between the side walls of the 10 furnace is directly exposed to the fire gases flowing from said chamber over said bridge wall through said flue, said still being so disposed as to leave between the bottom thereof and the top of the bridge wall a distance 15 of upwards of a third of the diameter of the still, substantially as described.

6. A high pressure petroleum still of horizontal cylindrical form provided with heating means which comprise (1) an open topped fire chamber, (2) an open topped heating flue 20 communicating with said fire chamber by an open topped passage over the bridge wall of the latter, and (3) supplementary firing appliances within said flue, 25 arranged to produce flames at numerous points covering the main part at least of the area between the said bridge wall and the end of the still, said still being so disposed as to leave between the bottom thereof and the top of the bridge wall a distance of upwards of a third of the diameter of the still, 30 substantially as described.

7. The method of firing a high pressure petroleum still in a distillation wherein petroleum in batches is gradually heated to 35 above 700° F. and is subsequently maintained at decomposing temperatures above 700° F. under appropriate superatmospheric pressure, which method consists in bringing flames into contact with the still bottom, feeding air to the fuel producing said flames 40 at a higher rate while the still contents are below said temperature of 700° F. than it is subsequently fed thereto, and so adjusting 45 (1) the inflow of air and (2) the withdrawal of combustion products while distilling at temperatures above 700° F. that the direction of the flames on reaching the still bottom shall then be more nearly horizontal 50 than vertical, the free space below the still bottom being sufficient for decomposing temperatures appropriately above 700° F. to be maintained in the still by the flames thus reaching said still bottom in a direction 55 more nearly horizontal than vertical, substantially as described.

8. The method of firing a high pressure petroleum still at decomposing temperatures above 700° F. by means of an open 60 topped fire chamber and an open topped flue, both of them underlying said still, and communicating with each other by an open topped passage above a bridge wall under the still bottom at a distance therefrom of 65 upwards of a third of the diameter of the

still, which said method consists in burning the fuel for heating the still mainly in said fire chamber but in part also in said open topped flue, with production of flames at numerous points covering the main part at least 70 of the area between said bridge wall and the end of the still, and so adjusting the inflow of air and the withdrawal of the combustion products that the direction of the flames on reaching the still bottom above 75 said bridge wall shall be more nearly horizontal than vertical, substantially as described.

9. A high pressure petroleum still with a capacity of not less than about one thousand cubic feet and of horizontal cylindrical form, provided with heating means which are so proportioned relatively to the capacity of said still as to maintain the latter with its charge of petroleum at decomposition temperatures above 700° F. and which comprise (1) an open topped fire chamber, (2) an open topped heating flue 80 communicating with said fire chamber by an open topped passage over the bridge wall 90 of the latter, so that the still bottom above said bridge wall and elsewhere over substantially its entire area between the side walls of the furnace is directly exposed to the fire gases flowing from said chamber over said bridge wall through said flue, and (3) supplementary firing appliances within said flue arranged to produce flames at numerous points covering the main part at least of the area between said bridge wall and the end of the still, said still being so disposed as to leave between the bottom thereof and the top of the bridge wall a distance of upwards of a third of the diameter of the still, 95 substantially as described.

10. The method of firing a high pressure 100 petroleum still, with a capacity of not less than about one thousand cubic feet and of horizontal cylindrical form, overlying an open topped fire chamber and an open topped flue which communicates with each other by an open topped passage above a bridge wall that is located at a distance from the still bottom of upwards of one-third 105 of the diameter of the still, the said still being also provided with manhole and vapor discharge fittings and with means for holding the still contents under appropriate superatmospheric pressure during distillation, substantially as described.

11. The method of firing a high pressure 110 petroleum still, with a capacity of not less than about one thousand cubic feet and of horizontal cylindrical form, overlying an open topped fire chamber and an open topped flue which communicates with each other by an open topped passage above a bridge wall that is located at a distance from the still bottom of upwards of one-third 115 of the diameter of the still, the said still having previously been charged with pe- 120

125

130

troleum of appropriate character in suitable volume, which said method consists in (1) burning the fuel for heating the still mainly in said fire chamber but in part also 5 in said open topped flue with production of flames at numerous points covering the main part at least of the area between said bridge wall and the end of the still, (2) bringing flames and fire gases directly into contact 10 with the bottom of said still above said bridge wall and elsewhere over substantially the entire area of said still bottom between the side walls of the furnace, (3) producing said fire gases in sufficient volume and at 15 sufficient temperatures to raise the contents

of the still to decomposing temperatures above 700° F., (4) feeding air at the rate of about ten per cent per minute of the capacity of said still to the fire in said chamber as a standard, and (5) regulating the withdrawal of combustion products from 20 said flue at such rate that the flames from said fire chamber on reaching the still bottom above said bridge wall shall have become more nearly horizontal than vertical, 25 as may be perceived by inspection through a peep hole, substantially as described.

In testimony whereof I affix my signature.

CHARLES E. STOCKFORD.
